UNITED STATES PATENT OFFICE.

HUGH DRYSDALE, OF CLEVELAND, OHIO.

ANIMAL-CLIPPING MACHINE.

SPECIFICATION forming part of Letters Patent No. 558,640, dated April 21, 1896.

Application filed June 1, 1891. Serial No. 394,810. (No model.)

To all whom it may concern:

Be it known that I, HUGH DRYSDALE, a citizen of the United States, residing at Cleveland, in the county of Cuyahoga and State of Ohio, have invented a new and useful Animal-Clipping Machine, of which the following is a description sufficiently full, clear, and exact to enable any person skilled in the art or science to which said invention appertains to make and use the same, reference being had to the accompanying drawings, forming a part of this specification, in which—

Figure 1 is a vertical longitudinal side view of the entire machine. Fig. 2 is a front view of the drop-arm; Fig. 3, a vertical section of said drop-arm, taken between the dotted lines $c' c'$ and $b' b'$ of Fig. 1, showing the manner of coupling the clipping device to the drop-arm and drive-shaft, also the manner in which 15 the clipping device swivels with respect to the drop-arm; Fig. 4, a front view of the rotating frame as it appears after the removal of the balance-beam and stand; Fig. 5, a vertical sectional view of the rotary handle and the 20 mechanism immediately connected therewith for operating the cutter and a sectional perspective view of the clipping mechanism and tension device. Fig. 6 is a longitudinal perspective view of the vertical back and comb- 25 plate. Fig. 7 is a perspective view of the presser-plate upside down, showing guide-pins for cutter-plate; Fig. 8, a plan view of the cutter-plate; Fig. 9, a plan view of the back of the drive-head, showing slot and ball; Fig. 10, a plan view of the rotary handle and 30 clipping device, the handle-hull shown in lateral section; Fig. 11, a vertical section view of the rotary handle and clipping device, taken on the dotted line $G' G'$ of Fig. 10, showing the connection of the drive-head with respect to the drive-shaft, vertical back, and 35 cutter-plate.

Like letters of reference indicate corresponding parts in the different figures of the 40 drawings.

My invention relates to that class of animal-clipping machines which are designed to be operated by the hand or by power; and it consists in a novel construction and arrangement of the parts, as is hereinafter more fully set forth and claimed, by which a more effective device of this character is produced

than is now in ordinary use, and the nature and operation of the improvement will be readily understood by all conversant with 55 such matters from the following explanation.

In the drawings, A represents the stand or body, B B B its legs, C a rotary frame secured on the top of stand, and F a balance-beam sustained in said stand and supporting 60 the drop-arm I, constituting the framework of the machine. The beam F carries on its rear end a counterbalance L, that is rendered adjustable thereon by means of the set-screw L'. On the forward end of same is permanently 65 secured an L-shaped lug G, the lower portion of which is hinged to and between the bifurcated drop-arm I by means of the shaft H passing through the extensions $e' e'$ of said arm and said lug that said arm may be swung 70 to or from the body of the machine, as referred to hereinafter. Said beam F is secured in a bearing provided in the arm extension D of the shaft X by means of a set-screw, as shown in Fig. 4, the threaded portion of which 75 enters a transverse slot or groove in the beam that prevents end motion of said beam in said arm and permits of a rotary motion of said beam in said arm to the extent of the slot or groove in said beam, that the drop-arm I aforementioned may be swung to the right or the 80 left of the perpendicular thereof, and at the same time be tilted up or down on the shaft X in conjunction with the to-and-from swinging motion aforescribed, thus giving to the 85 drop-arm a great range of motion. Within the hollow of said drop-arm I is provided a shaft d, (see Fig. 3,) with suitable bearings on the boss c and in the socket-piece y, and is secured in place by means of the bevel-gear a^5 , pinned to upper end of shaft and resting 90 on said boss. A slotted socket-piece is pinned to the lower end of same, that shoulders within the socket-piece y, that prevents end play of said shaft in said arm, and referred to hereinafter. The socket-piece y is 95 recessed to correspond with the shouldered end of the L-shaped lug J, and these parts are secured together swivel-like by means of the screws $e e$, or their equivalent, extending 100 from the sides of said socket-piece under said shoulder in such a manner that said lug may be readily rotated therein and by said means is said lug J coupled to or uncoupled from

the drop-arm I and swivels with respect thereto.

- The L-shaped lugs J and P are provided with gear-pits f and f'. Their corresponding extensions are journaled, male and female, as shown in Fig. 5, and are secured together by means of the shaft g', extending through them, with bevel-gears a² and a³ pinned on either end thereof within said pits, which prevents 5 said lugs from separating, but permits them to revolve one over the other. Said lug J is provided with a shaft g, that carries on its lower end a bevel-gear a', that meshes into and drives the gear a². The upper end of said 10 shaft extends out of the lug and is provided with a washer h, secured with a pin that prevents end play of said shaft in said lug. The outward-extending portion of said shaft g carries a drive-pin that corresponds to the 15 recessed and slotted socket-piece l, carried on the shaft d aforementioned, engages therein, and is driven thereby. Thus it is obvious that the shafts d and g' are coupled to or uncoupled from each other simultaneously with 20 the coupling or uncoupling of the lug J to the drop-arm I aforesaid. A shank-piece y is formed with a journal y' and a transverse vertical back m and is secured to the L-shaped lug P by means of the shaft g', extending through them, with a bevel-gear a⁴ pinned on one end, that meshes into and is driven by the bevel-gear a³. On the opposite end is pinned the disk u, that shoulders within the axial bore of the vertical back m, 25 that prevents end play of said shank, but permits rotary motion thereof. Thus it will be seen that the shank y is rotated on the shaft g, revolved on the lug P and swiveled on the lug J in the socket y with respect to 30 the drop-arm I. A tubular handle k (shown in lateral section in Fig. 10) is secured to a shoulder extension y' on the vertical back m by a driving fit, and by which the cutting parts are directed on the animal in the hand 35 of the operator. Extending forward from the lower edge of said vertical back m are two base-blocks n' n', (see Figs. 6 and 11,) to the under side of which is secured by screws a comb-plate x of the usual construction, and 40 from each end of said back m are two similar extending ears n n, one above the other, which are provided with pins o o, secured screw-like therein, that serve as a supporting-slideway 45 for a drive-head z, referred to hereinafter.
- 50 The drive-head consists of a rectangular-shaped block z. A vertical view of the back of same is shown in Fig. 9 and a top plan view in Fig. 10, and has a downward extension v, transverse slideways corresponding 55 to the slide-pins o o aforementioned, a round recess z² vertically let therein from the top, with a mill cut or slot from the back into said recess, and carries a ball t and cap-piece F' corresponding thereto, and referred to hereinafter. Said drive-head z is slidably mounted 60 on said slide-pins independent of the vertical back m and cutter-plate s, but in suit-

able contact therewith, the downward extension v engaging with the notch s² in the cutter-plate s, (see Fig. 8,) and the ball t has an 70 opening corresponding to the crank-pin and engages thereon, as shown in Fig. 11. Thus it is obvious that by rotating the disk u said head is reciprocated on said pins, and with it said cutter-plate on the comb-plate x, by reason of their engagement, as above described. 75

I make use of the round recess z², and the ball t therein, for connecting the crank-pin with the drive-head, as affording a most perfect connection of the crank-pin and head 80 with the least possible friction. I separate the drive-head from the cutter-plates, as described, that all the knock and jar caused by the crank-pin in its circular path will be retained within said head and on said pins, so 85 as not to interfere with the tensioning of the cutter-plates, referred to hereinafter.

The cutter-plate s, reciprocated on the comb-plate x, as above described, is guided in its lateral reciprocation by means of the 90 two guide-pins q² q³, extending downward from under side of presser-plate q (see Fig. 7) and extend through rectangular slots s' s' in the cutter-plate into corresponding openings in the comb-plate, the rear edge resting 95 on the base-blocks n' n', the forward edge resting on the forward edge of the cutter-plate s, and secured to the comb-plate x by means of the binding-screw w and thumb-nut p. Said screw is introduced therein from 100 under side of comb-plate x and extends upward through suitable openings provided in all three plates x, s, and q and part way through the thumb-nut p, it being threaded to correspond to said binding-screw. The 105 manipulation up or down of said nut on said screw causes the presser-plate to clamp the cutter-plate s to the comb-plate x and create a tension of the cutter-plates more or less tight, as the tension desired to clip the hair 110 may require. The tension thus required is maintained by means of the set-screw r, having a thread corresponding to that in said nut, and is entered from the top and forced against the end of said binding-screw, that 115 cramps the thread of the nut in opposite directions, thus causing a frictional lock of the nut and binding-screw that is of sufficient strength to hold any desired tension from changing by reason of jostling or hard usage 120 and is of such a nature as to be quickly and easily reset to any desired tension. I secure and tension the cutter-plates, as above described, independent of the drive-head z, in 125 order to avoid in said knives the knock and jar that is common in said head, to leave the cutter-plate s free to move on the comb-plate sensitively subject to its tension.

The shaft H aforementioned, besides hinging the drop-arm I to the beam F, carries on 130 one side of the lug G a bevel-gear a, that meshes into and drives the bevel-gear a⁵, and the continuous shafts d, g, g', and g² and their respective trains of bevel-gears, together with

the disk u , drive-head z , and cutter-plate s . On the opposite portion of said shaft H is carried the band-wheel b , that is connected by means of the belt Q to the fly-wheel R , carried on the shaft E in the frame C . The revolving of said wheel R imparts motion to the band-wheel b , shaft H , gear a , and the continuous line of incased shafts, drive-head, and cutter-plate aforescribed. The shaft E also carries a pinion S , that is geared into and is driven by the gear-wheel T , carried on the shaft W . Said shaft may be driven by a handle O or by a belt from a power passing around the pulley N . The legs of the machine are threaded into the downward extensions of the plate A . Upright columns U support a table-plate A' , upon which is secured a corresponding base-plate V of the frame C by means of the base-bolt M , that permits the stand C to rotate upon the body A' in conjunction with the up-and-down rocking of the balance-beam F , and the to-and-from and the lateral swing of the drop-arm I aforescribed. The drop-arm I is calculated to furnish bearings for the shafts and their gears and to carry the clipping device independent of said shafts in such a manner that they are properly united, but free from the weight thereof or the friction caused from cramp or twist in operating the drop-arm and clipping parts over the animal. Said drop-arm also serves to shield the operator and prevent foreign substance from wrapping on said shafts when in motion.

Having thus described my invention, what I claim, and desire to secure by Letters Patent, is—

1. In an animal-clipping machine, the cutter-carrier consisting of a shank-piece y , terminating in a back m , and formed with projecting base-blocks $n' n'$, similar extending ears $n n$, in combination with a comb-plate x , a cutter, means for operating the same, slide-pins $o o$, and a handle-case k , substantially as set forth.

2. In an animal-clipping machine, the cutter-carrier consisting of a shank-piece y , vertical back m , formed with base-blocks $n' n'$, similar extending ears $n n$, slide-pins $o o$,

comb-plate x , and handle-case k , in combination with a drive-head z , cutter-plate s , presser-plate q , and means for reciprocating said drive-head and cutter-plate.

3. The drive-head z , having a recess and slot z^2 , transverse slideways, cap-piece F' , covering said recess, a ball t , engaging a crank-pin on the disk u , and a downward extension v , engaging the cutter-plate, and means for reciprocating said head.

4. In an animal-clipping machine the drop-arm I consisting of a tubular extension Z , and formed with a socket-piece y , swiveling with respect to the swivel-arm, one end bifurcated and hinging with respect to the balance-beam F , in combination with a shaft d , incased and supported in bearings within said arm independent of the swivel-arm and rotating handle, substantially as set forth.

5. The combination in an animal-clipping machine, of a drop-arm I , incasing and supporting a shaft d , and having a socket-piece y , and means of engagement $e e$, with a swivel-arm J , and shaft g , independent of the shaft d .

6. The combination in an animal-clipping machine, of a shaft d , supported and incased within a drop-arm I , and having a slotted socket-piece l , with a swivel-arm J , having a shaft g , and a coupling-pin i , engaging with said slotted socket-piece, substantially as set forth and for the purpose specified.

7. In an animal-clipping machine, the rotating frame consisting of a base-plate V , formed with standards c , and having bosses and bearings therein suitable for the shafts $W E$ and X , in combination with the shaft W , carrying a band-wheel N , gear-wheel T , a shaft E , carrying a pinion S , and grooved wheel R , a shaft X , formed with an arm extension D supporting the balance-beam F , in a rotary and tilting manner, substantially as set forth.

In testimony whereof I sign this specification, in the presence of two witnesses, this 25th day of May, 1891.

HUGH DRYSDALE.
